FLOATING ROOF DRAIN

Ernest E. Michaels, Birmingham, Ala., assignor
to Chicago Bridge & Iron Company, a corpora-
tion of Illinois

Application April 24, 1946, Serial No. 664,679

2 Claims. (Cl. 220—26)

1

This invention relates to a drain for a floating roof tank or the like whereby water is drained from the roof when it reaches a certain predetermined depth on the roof.

In floating roof tanks the roof floats on top of the stored liquid and rises and falls as the amounts of liquid are increased and decreased. When rain water falls on the roof its weight decreases the buoyancy of the roof until the water is drained therefrom. Various means have been proposed for draining this water from the roof, but many of these have the disadvantage of permitting vapors to escape from the storage portion of the tank.

The drain shown and described herein is automatic in operation in that it only operates after a predetermined amount of water has collected on the roof. The drain is very simple in construction and may be easily removed for inspection. The new drain comprises broadly a buoyant member adapted to be immersed in the liquid contents of the tank and a valve seated in an opening in the roof and attached to the buoyant member and normally held closed by the buoyancy of the buoyant member. This valve is displaceable downward by a predetermined depth of water over it, sufficient in weight to overcome the buoyancy of the buoyant member. The buoyant member and valves are preferably movable in a substantially vertical path, and are guided in their movements by a housing around the buoyant member and supported on the lower surface of the roof around the valve.

The invention will be described as related to the embodiment set out in the accompanying drawings. Of the drawings Fig. 1 is a vertical section through substantially the center of the drain and through a portion of the roof; Fig. 2 is a plan view of the drain; and Fig. 3 is an elevation of an alternate type of buoyant member; and Fig. 4 is a plan view of the buoyant member of Fig. 3.

The valve shown in the accompanying drawings comprises a substantially circular plate 10 adapted to be bolted over a circular hole 11 in the deck 12 of a floating roof. In the plate 10 there is located an opening 13 having sides sloping inwardly and upwardly and normally closed by a valve 14. Beneath the valve 14 there is located a spherical float 15 connected by a substantially vertical stem 16 to the valve 14. Surrounding the float 15 is a cylindrical housing 17 of slightly greater diameter than the float. This housing has its top edge attached to the plate 10 around the valve 14. The bottom

2

of the housing 17 is normally closed by a flat plate 18 having an opening 19 therein. The plate 18 is attached to the housing 17 by means of bolts 20, and may be removed so that the float 15, stem 16, and valve 14 may be removed downwardly through the bottom end of the housing 17.

The valve 14 is provided with radial guides 21 on its bottom surface extending to points adjacent the housing 17. These guides serve to center the valve within the housing.

The roof of the floating roof tank is provided with pontoons 22.

As soon as a predetermined depth of water has 15 collected on the roof and over the plate 10 the weight of the water over the valve 14 causes the valve to be pushed downwardly against the buoyancy of the float 15. The water then flows through the opening 13 into the cylindrical housing 17 around the float 15 and out through the opening 19 in the bottom of the housing to the bottom of the tank. This causes the depth of water on the roof to be decreased until it is no longer sufficient to hold the valve 14 open. 20 At this point the buoyancy of the float 15 causes the valve 14 to again rise in the housing 17 until the opening 13 is again closed. As can be seen, the valve is entirely automatic in operation, and serves to keep the water on top of the roof at substantially a constant depth.

The predetermined depth of water on the roof depends upon the buoyancy of the float 15 and the area of the top surface of the valve 14. The buoyancy of the float equals $wh\pi r^2$, where r is the radius of the top surface of the valve 14, h is the predetermined depth of water, and w is the weight of a unit volume of water. When all dimensions are in inches w will equal 0.0362 lb.

As the plate 10 is held in position by bolts 23 35 and the entire drain is mounted on this plate the drain may be inserted and removed as a unit. A gasket 24 is provided between the plate 10 and the deck 12 in order to form a vapor-tight seal.

When the drain is first put into operation the 45 liquid level within the housing 17 will be at some point such as is indicated at 25. The liquid level on the outside of the housing 17 will be substantially the same until vapors form under the roof. This vapor pressure will then 50 cause the liquid level on the outside of the housing to be at some lower level as indicated at 26. Any type of vent means may be provided for venting the vapor when the vapor pressure exceeds a desired value.

As the cylindrical housing 17 is always im-

mersed in the stored liquid, vapor losses through the opening 13 while the roof is draining are limited to the small amount of vapor within the housing.

Figs. 3 and 4 show an alternate type of float. This float 27 is of cylindrical shape and may be used instead of the spherical float 15. Any other type of float may be used if desired.

Although the plate 10 is shown and described as being circular it may be polygonal or any other desired shape. Similarly the valve 14 may have any desired shape and the float 15 need not be spherical or cylindrical but may be any other shape.

Having described my invention as related to the embodiments set out in the accompanying drawings, it is my intention that the invention be not limited by the details of description unless otherwise specified, but rather be construed broadly within its spirit and scope as set out in the accompanying claims.

I claim:

1. In combination with a floating roof tank, a drain for the deck of the roof comprising a sump in the deck, said sump having an opening in its bottom located above the level of the liquid in the tank and opening to the space beneath the deck, a cylinder in vertical alignment and communication with said opening and extending substantially vertically downwardly from the sump and into the liquid in the tank, a valve beneath the opening and adapted to move upwardly to

close the same, a float in the cylinder and a rod connecting the float and valve, said rod having a length greater than the distance between the valve and the liquid level whereby to immerse the float in the liquid to maintain constantly an upward pressure on the valve when the roof is floating in the liquid, said valve having a predetermined horizontal area exposed to liquid in the sump and said sump having a depth to entrap a sufficient head of drain water above said area to overcome said upward pressure and open the valve.

5 2. The drain of claim 1 in which said cylinder has a length greater than the combined length of the float and rod whereby said valve is moved downwardly away from the opening when the roof is not floating on liquid in the tank.

10 ERNEST E. MICHAELS.
